ART OF DISTILLING OILS

Application filed May 5, 1924. Serial No. 711,129.

The present application relates to improvements in the art of distilling oils, and more particularly in the continuous distillation of such oils wherein the greater proportion of the oils are removed by substantially non-cracking distillation, ordinarily with the aid of steam. It will be fully understood from the following description, illustrated by the accompanying drawings, in 10 which:

Figure 1 is a diagrammatic view of a layout of apparatus suitable for use in the present process; and

Fig. 2 is a sectional view on the line 2 of 15 the still of Fig. 1.

Fig. 3 is a perspective view of a perforated pipe employed with the apparatus.

Referring more particularly to the drawings, the numeral 5 indicates a still which 20 may suitably be the last member of a battery of continuous stills of the usual type, in which the oil is subjected to distillation by fire and steam either with or without the aid of vacuum, as desired. From the still 5 the 25 residue of the continuous distillation is drawn off through the valved pipe 6 by a surge pump 7 or other suitable pumping device through pipe 8 into and through the heating coil 9 (diagrammatically shown) 30 mounted in a suitable furnace setting 10. If desired, steam or other inert gas may be introduced into the oil in the coil through pipe 8a. From the coil 9 the oil passes through a pipe 11 into an enlarged chamber 35 12, which may suitably be of the form of a horizontal cylindrical shell.

Steam or other inert vapor from a supply line 13 passes through a superheating coil 14, which may suitably be mounted in the 40 heating coil setting 10, and from the superheater, the steam or other vapor passes through pipe 15 into the coil 16, which lies within the shell or chamber 12. The pipes of the coil 16 extend longitudinally of the 45 chamber and may be positioned near its inner wall, lying against the lower half thereof. From the coil, the steam passes into a distributing pipe 17 lying in the lower portion of the still near the inner wall and provided 50 with downwardly directed perforations,

through which the steam enters the body of oil in the still.

A body of oil is maintained in the chamber 12, its level being controlled by means of the float indicator or other suitable device 55 indicated by the numeral 18. Residue is drawn off through the valve draw off line 19 by means of a surge pump 20, the tar being discharged through the tar line 21. If desired, a flowing oil, such as the oil 60 condensed in the condenser 24 hereinafter referred to, may be introduced into the bottom through line 21a.

From the chamber 12 vapors pass off through a large dome and vapor line 22, 65 which are preferably insulated to prevent substantial reflux into the still. The vapors pass through a series of fractionating condensers 23, 24 and 25, the condensate formed in these condensers being drawn off through 70 a cooler 26 to a receiving tank 27. Vapors uncondensed in the last of the fractionating condensers 25 pass out through a vapor line 28 and a valved line 29 to a condenser 30. If desired, vapors and steam from the condenser 25 may be drawn off through the line 31, 75 provided with a valve 32, by means of a suitable blower 33 and forced through the line 34 connecting with the steam supply line 13 leading into the superheater coil 14. 80

In carrying out the invention, a suitable mineral oil of the nature of crude oil, which may be a crude oil or reduced crude oil, is subjected to continuous distillation with fire and steam in the battery of stills terminating 85 in the still 5. The distillation in this manner is carried to a heavy pitch-like bottom which may be, for example, in the case of a mid-continent crude from 6 to 10% of the original crude. For example, the temperature of the oil in the final still 5 of the battery may be from 650 to 750° F., the residue being a pitch of 10 to 16° Bé. and having a flash point of 450° F. or higher. 90

The hot tar is pumped continuously by 95 surge pump 7 from the still 5 into and through the heating coil 9. The oil is pumped at high velocity through this coil, in which it is rapidly brought to a temperature above decomposing temperature, and prefer- 100

ably above 750° F., the rapid flow of the oil substantially preventing coke deposits therein. A suitable temperature for the oil at the outlet of the coil 9 is, for example, from 5 775 to 825° F. The oil is not retained in the coil for a sufficient period to cause substantial decomposition thereof. From the heating coil 9 the hot oil passes through the pipe 11 into the enlarged chamber 12, which is 10 of sufficient size to permit the oil to remain therein for a considerable period, preferably in excess of one hour. Steam is passed through the super-heating coil 14, in which it is brought to a temperature at least as high 15 as the temperature of the oil in the chamber 12, and preferably higher, say 900° F. to 1100° F., and is then forced through the coil 16 in the interior of the chamber 12, finally entering the distributing pipe 17 and passing 20 into the body of oil. The high temperature steam substantially maintains the temperature of the oil within the chamber 12 and materially aids the evaporation of the more volatile constituents of the oil formed therein. 25 Other inert gases or vapors, such as flue gas, natural gas, light oil vapors, etc., may be substituted for the steam, if desired. The system is maintained at substantially atmospheric pressure and an extremely rapid decomposition of the oil takes place in the 30 enlarged chamber 12. Ordinarily, from 30 to 60% of the oil is distilled off in the form of vapors of products of decomposition, leaving a tar which, in the case of a mid-continent 35 crude as above referred to, may be from 3 to 5% of the original crude. This tar is drawn off substantially continuously through the draw off pipe 19, for example, by the surge pump 20. The tar drawn off may be mixed 40 off with a hot and lighter oil, if desired, such as the condensate from the tower 24 and disposed of as fuel.

The vapors evolved from the oil in the chamber 12, together with the steam discharged thereinto, pass off rapidly through the vapor line 22, which is preferably insulated and so arranged as to avoid any substantial reflux into the chamber 12.

The vapors passing out of the still 12 50 travel successively through the fractionating condensers 23, 24 and 25, which are illustrated as being of a standard air-cooled type, but may be of any desired form. The successive fractions condensed in these fractionating condensers are removed through the cooling worms 26, passing into the receiving tanks 27. The operation of the fractionating condensers may be controlled in accordance with the characteristics of the desired products. 55 For example, it has been found convenient to cool the vapors in the first condenser 23 to 600 to 650° F.; in the condenser 24 to 500 to 550° F.; and in the condenser 25 to any suitable temperature, preferably above the 60 temperature of condensation of the steam.

In so operating, a condensate of the character of heavy oil may be formed in and removed from the condenser 23; a product of the character of gas oil in the condenser 24 and a kerosene-like product in the condenser 25. The vapors uncondensed in the last aerial condenser may pass through the lines 70 28 and 29 into the condenser 30, in which they may be condensed, forming gasoline-like and kerosene-like products. If desired the vapors issuing from the last fractionating condenser 25 may be forced by the blower 33 into the steam supply line 13 leading into the superheating coil 14. As these vapors consist largely of steam, the latent heat of 75 the steam and vapors thus reused is saved in this manner of operation.

In general, the present method of operation is applicable in connection with processes of continuous distillation in which crude oils 80 are reduced by non-cracking distillatory methods to heavy pitch bottoms of the order of 10 to 16° Baumé, or heavier. Although illustrated in connection with the treatment of mid-continent oils, it is readily apparent that 85 it may be employed in the treatment of any type of crude oil or oil of similar nature, as reduced crude oil, from which the utmost recovery of valuable products is desired. The decomposed tar drawn from the 90 enlarged chamber 12, in which the greater part of the decomposition of the oil takes place, has a relatively low viscosity as compared with a product bearing a like relation 95 to the original crude oil and obtained directly by steam and fire distillation, and consequently may be directly employed as a fluid fuel. The specific details of the process above set forth are not intended to be regarded as 100 limitations upon the scope of the invention, except insofar as included in the accompanying 105 claims.

We claim:

1. The method of distilling oils which consists in subjecting a crude oil to distillation under substantially non-cracking conditions to form a residue of a pitch-like character, forcing said residue from the distillation zone directly through a heating coil in a rapidly flowing stream, said coil being externally heated to impart to the residue oil a temperature of at least 750° F. without substantial decomposition thereof, passing the heated residue oil products from said heating coil into an enlarged chamber in which a body of unvaporized liquid is held and, wherein its temperature is substantially maintained, the unvaporized residue products being maintained in said chamber until a material decomposition thereof is effected, forcing an independent stream of heated inert gas through the liquid in said enlarged chamber, thereby aiding the removal of vapors of products of decomposition, drawing off said vapors and inert gas and 115 separating the residue oil products from the 120 inert gas.

rately drawing off liquid tar from said enlarged chamber, approximately atmospheric pressure being maintained on said enlarged chamber.

5 2. The method of distilling oils which comprises subjecting a crude oil to distillation under non-cracking conditions to form a residue of 10 to 16° Baumé, removing said residue from the distillation zone and passing 10 it, while hot, through a heating zone in a rapidly flowing stream, the applied temperature being such as to raise the temperature of the oil to above decomposing temperature, and passing the heated liquid oil directly 15 into an enlarged chamber maintained approximately at atmospheric pressure, applying heat interiorly of the enlarged chamber to maintain the temperature of the oil therein at above cracking temperature, passing 20 super-heated steam into said oil, thereby aiding in the removal of vapors of products of decomposition, a body of residue oil being retained in said enlarged chamber until a material decomposition is effected, removing 25 and fractionally condensing the vapors evolved in said enlarged chamber, and separately removing the liquid residuum therefrom.

3. The method of distilling oils which comprises reducing a crude oil by means of fire and steam to a heavy residue, said residue having a temperature of approximately 700° F. in the distilling zone, removing said residue and applying heat thereto 35 while in a rapidly flowing stream to bring said residue oil to a temperature of 800° F. or higher passing said heated residue oil into an enlarged chamber, maintaining the temperature of the liquid therein by interior- 40 ly applied heat, a material decomposition of said residue oil body taking place in the enlarged chamber, passing superheated steam into said oil body, thereby aiding the removal of vapors of products of decomposition, 45 fractionally condensing said vapors, and removing the tar from said enlarged chamber.

4. The method of distilling oils which consists in subjecting a crude petroleum oil to distillation under substantially non-cracking 50 conditions to form a residue of a pitch-like character, forcing said residue from the distillation zone directly through a heating coil in a rapidly flowing stream, said coil being heated to impart to the residue oil a temperature above decomposing temperature without substantial decomposition thereof, passing the liquid residue oil from said heating coil into an enlarged chamber in which a body of said residue is maintained until a 55 material decomposition thereof is effected, superheating steam to a temperature at least as high as that of the oil in said chamber, passing the steam through a closed passage within the chamber in indirect heat conductive contact with the oil therein, thereby 60

maintaining the temperature of said oil, subsequently discharging the steam into said oil within said chamber, and maintaining substantially atmospheric pressure in the chamber.

5. The method of distilling a heavy, pitch-like residue from the substantially non-cracking distillation of crude petroleum oil which comprises forcing said residue, previously heated to a temperature of at least 650° F., 70 through a heating coil in a rapidly flowing stream, said coil being heated to impart to the residue oil a temperature above decomposing temperature without substantial decomposition thereof, passing the heated oil 75 from said heating coil into an enlarged chamber, in which a body of said oil is maintained, superheating steam to a temperature at least as high as that of the oil in said chamber, 80 passing the heated steam in a closed passage within said chamber in indirect heat conductive contact with the oil therein, thereby maintaining the temperature of the latter while decomposition thereof is effected, and subsequently discharging the steam into said 85 body of oil.

6. The method of distilling a heavy, pitch-like residue from the substantially non-cracking distillation of crude petroleum oil which comprises forcing said residue, previously 90 heated to a temperature of at least 650° F., through a heating coil in a rapidly flowing stream, said coil being heated to impart to the residue oil a temperature above decomposing temperature without substantial decomposition thereof, passing the heated oil 95 from said heating coil into an enlarged chamber, in which a body of said oil is maintained, superheating steam to a temperature at least as high as that of the oil in said chamber, 100 passing the heated steam in a closed passage within said chamber in indirect heat conductive contact with the oil therein, thereby maintaining the temperature of the latter while decomposition thereof is effected, and subsequently discharging the steam into said 105 body of oil.

7. The method of distilling a heavy, pitch-like residue derived from the substantially non-cracking distillation of crude petroleum oil which comprises passing such residue, previously heated to liquefaction temperature, through a heating zone in a rapidly flowing stream, wherein the residue oil is brought to a temperature above decomposing temperature without substantial decomposition thereof, passing the heated residue oil directly into an enlarged chamber in which a body of oil is maintained, applying heat interiorly of the enlarged chamber to maintain the temperature of the oil therein at above decomposition temperature a material decomposition of the oil being effected therein, 115 120 125 130

and passing steam into the body of oil in the chamber.

8. The method of distilling a heavy, pitch-like residue derived from the substantially non-cracking distillation of crude petroleum oil which comprises passing such residue, previously heated to liquefaction temperature, through a heating zone in a rapidly flowing stream, wherein the residue oil is brought to a temperature above decomposing temperature without substantial decomposition thereof, passing the heated residue oil directly into an enlarged chamber in which a body of oil is maintained, applying heat 10 interiorly of the enlarged chamber to maintain the temperature of the oil therein at above decomposition temperature, a material decomposition of the oil being effected therein, and passing steam into the body of oil in the chamber, while maintaining substantially atmospheric pressure in said chamber.
